UNITED STATES PATENT OFFICE.

JOHN F. O'CONNOR, OF CHICAGO, ILLINOIS, ASSIGNOR, BY MESNE ASSIGNMENTS, TO
W. H. MINER, INC., A CORPORATION OF DELAWARE.

ANTIFRICTION BEARING.

Application filed August 29, 1924. Serial No. 734,634.

This invention relates to improvements in anti-friction bearings.

One object of the invention is to provide a simple, practical and relatively inexpensive roller bearing, especially adapted for railway car side bearings, in which the parts are so arranged that the anti-friction element is automatically returned to normal centered position under the influence of gravity when free from the load.

Another object is to provide an anti-friction bearing of this character, including a rocker having a support adapted to normally bodily support an anti-friction roller during the rocking movement of the rocker within certain limits, such roller being held against relative movement with respect to the rocker during this period, together with independent bearing means which are provided for receiving the trunnions of the roller, and supporting the same for unlimited rotation when the rocker is moved beyond the limits of the normal rocking movement thereof.

Other and further objects of the invention will more clearly and fully appear from the description and claims hereinafter following.

In the drawing forming a part of this specification, Figure 1 is a vertical, partial sectional view taken through the ends of the body and truck bolsters of a railway car showing my invention in connection therewith. Figure 2 is a sectional view of the invention on line 2—2 of Figure 1. And Figure 3 is a side elevational, detail view of the rocker used in connection with my invention.

Referring to the drawings, A indicates the underside of a body bolster, and B the upper side of the corresponding spaced truck bolster. My improved side bearing is shown as applied to the truck bolster, and comprises broadly, a mounting in the form of a housing C, an anti-friction element D, and a rocker E to which the anti-friction element is connected.

The housing C is provided with curved end walls 5, and flanges 6, adapted to be secured to the bearing plate 7 by means of rivets 8, the bearing plates 7 in turn being secured to the bolster B, by means of rivets 9. The housing C has its opposite side walls off-set so as to form guides 10, the upper portions of such guides being arranged to provide longitudinally separated, semi-circular bearing seats 11, for the accommodation of the trunnions of the anti-friction element D in cer-

tain positions of the parts, the guides 10 serving to limit the rocking movement of the rocker E as will presently appear.

The rocker or supporting member E is provided with side standards 12, connected at their lower ends by an arcuate web or wall 13, a portion of which is offset to provide a supporting seat 14, adapted to accommodate the periphery of the anti-friction roller D when placed thereon. The lower curved surface of the rocker E, as indicated at 15, is adapted to rock upon the bearing plate 7. The outer sides of the rocker E are preferably provided with segmental extensions 16, arranged to be disposed within the guides 10, and co-operating therewith to limit the rocking movement of the rocker E.

The standards 12 of the rocker E are provided with bearing openings 17, to accommodate the trunnions 18 of the anti-friction element D, such openings being somewhat elongated so as to provide limited play of the trunnions 18 radially with respect to the curved bearing surface of the rocker E as clearly shown in the drawings. The trunnions 18 extend beyond the standards 12 a suitable distance, the ends of which are normally disposed in the curved bearing portions 19 of the extensions 16, the trunnions being so arranged that at the limit of the rocking movement of the rocker as permitted by the abutment of the extensions 16 and the guides 10, the trunnions move onto the bearing seats 11, this movement being permitted by the limited play of the trunnions 18 in the bearing openings 11, and serving to move the roller free of the support 14.

In operation of the device, assuming that the roller and rocker are moving toward the right as shown in dotted lines in Figure 1, during the normal position and the normal portion of travel, the roller and rocker are held against relative movement, and move in unison transmitting the load bodily through the roller D and rocker to the bearing plate 7, this rocking movement continuing until the adjacent surfaces of the extensions 16 abut against the guides 10, whereupon further rocking movement is prevented. Upon further relative movement of the bolster parts beyond the limits of the rocking movement of the rocker, the periphery of the roller will be moved out of engagement with the support 14, and the trunnions 18 will come into engagement with the bearing seats 11, thereby

transferring the support of the roller to the independent bearings so as to permit unlimited rotation thereof. When the load is released from the roller, the rocker, due to its unbalanced condition, will return to its normal position, carrying the roller with it, during which movement the trunnions 18 return to the lower ends of the openings 17, and the roller will again bear upon the supporting seat 14, so as to transmit the load bodily through the roller to the bearing plate 7.

By the above described arrangement independent bearing means are provided which are automatically engaged during the movements of the parts for supporting the roller for unlimited rotation, and the rocker of course acts as a counter-balance for the roller, as well as a positive support therefor. It will also be noted that the parts at all times, except at the limit of the movement of the rocker, operate as a unit, and the load is bodily transmitted through the roller and through the rocker to the bearing plate 7.

I have herein shown and described what I now consider to be the preferred manner of carrying out my invention, but the same is merely illustrative, and I contemplate all changes and modifications that come within the scope of the claims appended hereto.

I claim:

1. In an anti-friction bearing, the combination with relatively movable bearing members; of a rocker disposed therebetween; and anti-friction element supported by said rocker, said element and said rocker being connected and arranged to move as a unit during a portion of the rocking movement, said element and rocker being constructed to permit movement of said element out of engagement of the support afforded by said rocker; and means independent of said rocker arranged to support said element for rotation when said element is removed from supporting engagement with said rocker.

2. In an anti-friction bearing, the combination with relatively movable bearing members; of a rocker disposed therebetween; of means for limiting the movement of said rocker; an anti-friction element; and means operatively connecting said element and said rocker, said means being arranged to retain said element against movement relative to said rocker at all points within the limits of its rocking movement; and means independent of said rocker and arranged to support said element for rotation at points beyond the limits of movement of the rocker.

3. In an anti-friction bearing, the combination with relatively movable bearing members; of a rocking self-centering supporting member interposed therebetween; bearing means independent of said supporting member and spaced with reference thereto; an anti-friction element normally supported on said supporting member and cen-

tered thereby, said supporting member being arranged to transfer the support of said anti-friction element to said independent bearing means, during a portion of its movement; and means connecting said anti-friction element with said rocking supporting member.

4. In an anti-friction bearing, the combination with a relatively movable bearing members; of a rocker interposed therebetween, and having a curved bearing portion, said rocker being provided with spaced standards having elongated journal bearings therein, said bearings being radially disposed with respect to the curved portion of said rocker; an anti-friction element having trunnions disposed in said journal bearings, said element being adapted to normally be supported by said rocker; means for limiting the movement of said rocker; and independent bearing seats arranged to receive the trunnions of said element and support the same for rotation beyond the limits of its rocking movement.

5. In an anti-friction bearing, the combination with a housing having a bearing surface; of a rocker disposed upon said bearing surface and adapted to rock thereon, said rocker being provided with a curved seat; an anti-friction roller loosely disposed in said seat and having its circumferential tread bearing against said seat, said rocker and roller being so constructed that movement of the rocker and roller is in unison for a limited distance to either side of central position and thereafter separation of said tread from bearing engagement with said seat, is permitted, said roller being provided with axially arranged trunnions; and fixed bearing means independent of said rocker adapted for the reception of said trunnions to support said roller for rotation about its axis when the roller is free of bearing contact with said seat.

6. In an anti-friction bearing, the combination with a retainer having a bearing surface; of a self-centering rocker mounted for rocking engagement with said bearing surface; an anti-friction element connected with said rocker, and maintained in centered position thereby, said rocker being provided with trunnions; and bearing means independent of said rocker and arranged at opposite sides thereof adapted for the reception of the trunnions on said anti-friction element upon movement of said rocker a predetermined distance to either side of central position.

7. In an anti-friction bearing including a retainer provided with side walls having vertically disposed guide means provided with oppositely arranged bearing seats; of a rocker having a supporting seat thereon and provided with extensions adapted to co-operate with said guide means to limit rocking movement of said rocker; an anti-friction element connected with said rocker and nor-

mally centered thereby and having its circumferential tread bearing on said seat, said anti-friction element being provided with axial projections adapted for engagement with the bearing seats in said guide means upon movement of said rocker to its extreme positions to either side of central position, the connecting means being constructed to permit separa-

ration of the circumferential tread of said anti-friction element from said seat at the 10 limitation of movement of said rocker.

In witness that I claim the foregoing I have hereunto subscribed my name this 26 day of August, 1924.

JOHN F. O'CONNOR.
